Specification for Design.

Patented Aug. 3, 1920.

Application filed October 10, 1919. Serial No. 329,859. Term of patent 7 years.

To all whom it may concern:

Be it known that I, BERNARD R. REYNOLDS, a citizen of the United States, residing at Kansas City, in the county of Wyandotte and State of Kansas, have invented a new, original, and ornamental Design for a Pin or Similar Device for Personal Wear, of which the following is a specification, reference being had to the accompanying drawing forming a part thereof.

In the drawing—

Figures 1 and 2 are front and side views, respectively, of a pin, showing my new design.

I claim:

The ornamental design for a pin or similar device for personal wear, as shown.

BERNARD R. REYNOLDS.
